UNITED STATES PATENT OFFICE.

CHARLES A. HAIST, OF FRESNO, CALIFORNIA.

FOUNTAIN PEN.

Application filed May 20, 1926. Serial No. 110,420.

The purpose of the invention is to provide a pen having means to quickly and fully charge the same with ink, after having been emptied; to provide a construction of this character in which the filling element is adjustable after charging, so that the ink may be readily forced to the pen point to avoid the necessity of shaking the pen, as is so common in devices of this character; and to provide a construction in which the charging element and its associated parts is readily removable from the barrel to permit the ready cleaning of both the charging element and the barrel.

With this purpose in view, the invention consists in a construction and combination of parts of which a preferred embodiment is illustrated in the accompanying drawings, wherein:

Figure 1 is a side elevational view of the invention, the guard cap for the pen point being broken away.

Figure 2 is a central longitudinal sectional view.

Figure 3 is a transverse sectional view on the plane indicated by the line 3—3 of Figure 2.

Figure 4 is a transverse sectional view on the plane indicated by the line 4—4 of Figure 2.

The barrel 10, which is of tubular form to provide a reservoir for the charge of ink, is interiorly threaded at both ends, the lower or forward end receiving the plug 11 which is exteriorly threaded, as indicated at 12, for engagement with the interior threads of the barrel. The outer end of the plug is recessed to receive and support the pen 14 which, when not in use, is shielded or covered by the cap 15 threaded to engage the exterior threads at the outer end of the plug, as indicated at 16. Communication between the pen and the interior of the barrel is effected by means of a duct or channel 17 formed axially through the plug.

The charging means consists of a plunger 18 snugly fitting the barrel and frictionally engaging the interior wall surface thereof, this plunger being mounted on an extension 50 stud 19 which passes centrally through the plunger, and seated against the outer or lower face of the latter is a washer 20 abutting a diametrical fastener 21 extending through the stud. The stud is formed as an integral axial extension of an interiorly 55 threaded stem 22, the sleeve being connected

with a screw 23 movable into and out of the sleeve by relative angular or turning movement of the two and therefore providing for axially extending or contracting the 60 plunger actuating means which consist of both the sleeve and the screw.

The screw 23 at its upper end is reduced, as indicated at 24, where it passes slidably through a plug 25, the latter being exteriorly 65 threaded and engaged with the interior threads at the remote end of the barrel from the plug 11. This plug 25 serves as a removable closure for the barrel at its end when it is desired to remove the charging 70 means, the plug having diametrically disposed sockets 26 engageable with pins 27 projecting from the lower face of a turning key 28, the latter being axially movable of the reduced portion 24 of the screw to 75 either engage or disengage it from the cross sectionally angular portion 29 of the latter, the screw being headed, as at 30, to provide an abutment for the turning key when engaged with the angular portion. Obviously, 80 when the key is engaged with the angular portion, it is disengaged from the plug 25 and turning movement then imparted to the key will result in rotating the screw and thus extending or contracting the plunger operating 85 means, since the frictional engagement of the plunger with the wall of the barrel will prevent turning movement of the plunger and the sleeve 22 with respect to the barrel with reference to which the screw 90 moves when being turned by the key 28.

Assuming the device to have been charged, the plunger operating means will be in the contracted position where the upper or rear end of the sleeve will abut the inner face of 95 the plug 25. The space between the plunger and the plug then defines the ink chamber. When the ink does not reach the pen freely because of a long period of disuse of the device, it may be readily started by shifting 100 the key into engagement with the cross sectionally angular portion 29 and, being turned in a reverse or anti-clockwise direction, will serve to advance the plunger 18 toward the plug 11 and thus force the ink to the pen. 105 When the contents of the barrel has been fully used up, the actuating means of the plunger will be in the full extended position and in charging the reverse operation may be performed; or the plug 25 may be disengaged from the barrel and the plunger extracted with the actuating means in ex-

tended position, when the screw may be rotated to full telescoped position within the sleeve and the plug 25 then attached.

A cap 31 is provided to enclose the key 28, 5 this cap being peripherally reduced, as at 32, and exteriorly threaded to engage the interior threads of the barrel above or below the plug 25.

The invention having been described, 10 what is claimed as new and useful is:

1. A fountain pen having a hollow barrel and a pen point carried at one end thereof and in communication with the interior of the barrel, a plunger mounted in the barrel, 15 actuating means for the plunger comprising an interiorly threaded sleeve connected with the plunger and a screw engaging and telescoping said sleeve, a plug in the barrel at the remote end from the pen and supporting 20 one end of the screw, and means for actuating the screw, said means comprising a key permanently mounted on the screw and axially movable thereof to lock it against

angular movement with respect to the screw or to free it from such movement. 25

2. A fountain pen having a hollow barrel and a pen point carried at one end thereof and in communication with the interior of the barrel, a plunger mounted in the barrel, actuating means for the plunger comprising 30 an interiorly threaded sleeve connected with the plunger and a screw engaging and telescoping said sleeve, a plug in the barrel at the remote end from the pen and supporting 35 one end of the screw, and means for actuating the screw, said means comprising a key permanently mounted on the screw and axially movable thereof to lock it against angular movement with respect to the screw or to free it from such movement, said key 40 having pins engageable in sockets in said plug to rotate and detach the latter when in unlocked position from the screw.

In testimony whereof he affixes his signature.

CHARLES A. HAIST.
